HINGE

John Ludwig, Detroit, Mich.

Application April 6, 1938, Serial No. 200,468

3 Claims. (Cl. 16—164)

My invention relates to a new and useful improvement in a hinge adapted for mounting a swingable closure on a stationary support and so arranged and constructed that none of the parts 5 of the hinge will be exposed to view when the closure is in closing position. The invention lends itself particularly for mounting doors on vehicle bodies so that the exterior surface of the vehicle body will be free from outward projections or obstructions.

It is an object of this invention to provide a hinge of this class which will be simple in structure, economical of manufacture, durable, compact, easily and quickly assembled and highly 15 efficient in use.

Another object of the invention is the provision of a hinge of this type possessed of a minimum number of parts.

Another object of the invention is the provision 20 of a hinge consisting of a pair of butts hingedly connected together, one of said butts being connected to the other by a pair of links each of which pivots at one end, the free end of said links swinging on intersecting arcs one of said arcs 25 being greater than the other, the link swinging on the greater arc being positioned outwardly toward the open end of the butt in which mounted.

Other objects of the invention will appear hereinafter.

The invention consists in the combination and arrangement of parts hereinafter described and claimed.

The invention will be best understood by a reference to the accompanying drawing which forms 35 a part of this specification, and in which:

Fig. 1 is a central, horizontal, sectional view of the invention showing the closure in closed position.

Fig. 2 is a central, horizontal, sectional view of the invention showing the closure in its initial position of opening.

Fig. 3 is a central, horizontal, sectional view showing the closure in fully opened position.

Fig. 4 is a sectional view taken on line 4—4 of 45 Fig. 1.

Fig. 5 is a sectional view taken on line 5—5 of Fig. 1.

Fig. 6 is a sectional view taken on line 6—6 of 50 Fig. 1.

In the drawing I have illustrated the invention adapted for mounting a closure 9 swingably on a stationary supporting body 10. One of the hinge butts comprises a U-shaped structure having the oppositely disposed legs 11 and 12 con-

nected by the bight 13. This butt is mounted in any suitable manner within the recess 14 of the supporting body 10. The cooperating hinge butt comprises the rod 15 having its end threaded for the reception of nuts 16 and 17 which serve to clamp opposite sides of a plate 18 on the swingable closure 9, the member 15, at its threaded end, projecting through the plate 18. This rod 15 is provided with the angularly turned portion 19 which extends angularly to the longitudinal 10 axis of the main body of the rod 15 and which terminates in an angularly turned portion 20 which extends parallel to the axis of the main body 15, these portions 19 and 20 being milled to provide flat opposite sides.

Pivoted, by means of the pin 21, to the legs 11 and 12 and lying between these legs are short links 22 and 23, the pin 21 passing through one end of these links. The opposite end of the links 22 and 23 are pivoted by means of the pin 24 which passes through the opposite end of said links and through the angularly turned portion 20. A pin 29 serves to pivotally mount one end of the links 27 and 28 on the U-shaped hinge butt, these links being formed arcuate as shown in Fig. 1 and Fig. 2. The opposite ends of these links are pivotally connected by means of the pin 30 to the hinge butt 15 at the juncture between the parts 19 and 20.

The construction is such that when the hinge is mounted in the manner indicated and as the movement of the closure 9 from closed position shown in Fig. 1 outwardly as illustrated in Fig. 2 and Fig. 3 is effected, the links 27 and 28 and the links 22 and 23 will each swing outwardly on their pivots 29 and 21, respectively. At the same time, the hinge butt 15 will rock on the pivot 30. This movement will continue until a point is reached at which the pivot 24 is about to align itself with the pivots 30 and 21 whereupon during a further outward swinging the links 27 and 28 will remain substantially stationary and the hinge butt 15 will rock on the pivot 30 until the pivots 21, 24 and 30 are in alignment. Upon a further opening movement, the pivot 24 will swing past center but in its swinging movement past center, the links 27 and 28 will swing slightly in the reverse direction and at this time, the angularly turned portion 19 will engage the stop lugs 31 which are struck inwardly from the legs 11 and 12. Embracing the pin or pintle 21 are the coils 32 and 33 of a spring which is double upon itself at its center and extended outwardly in the form of a tongue 34 to engage in a slot 35 formed in the bight 13. The ends of this

spring are turned outwardly as at 36 to engage the concave edges 26 of the links 27 and 28 when the closure swings to closed position so as to offer resistance to this swinging movement and 5 prevent a slamming of the door when moved to closed position. It will be noted that the spring is placed under tension as the swingable closure approaches fully open position. Thus the spring prevents a slamming of the door at either end of 10 its swinging movement.

The swinging of the links with the arcs defined by the pivots 24 and 30 struck on different sized radii and arranged in the manner illustrated, makes it possible to provide a concealed 15 hinge in which a secure and close closing of the door may be effected and an easy and silent opening of the same accomplished. By forming 20 the links 27 and 28 arcuate and facing them toward the part 24, a clearance is afforded for 25 the ends of the links 22 and 23 as they swing, as shown in Fig. 2, across the space defined by the links 27 and 28.

The terminal angularly turned portion 20 may be considered an offset of the angularly turned 25 portion 19 or a laterally projecting portion projecting laterally therefrom.

While I have illustrated and described the preferred form of construction, I do not wish to limit myself to the precise details of structure 30 shown, but desire to avail myself of such variations and modifications as may come within the scope of the appended claims.

What I claim as new is:

1. A hinge of the class described, comprising: 35 a hinge butt having a pair of spaced apart parts; a cooperating hinge butt comprising a main body having a laterally angularly turned portion; a lateral offset projecting outwardly from adjacent the end of said angularly turned portion and 40 extending in axial parallel relation to the longitudinal axis of said body; a pair of links pivotally mounted at one of their ends between said spaced apart parts and at their opposite ends to said lateral offset; a pair of links pivotally mounted at one of their ends between said 45 spaced apart parts and at their opposite ends to said angularly turned portion at substantially the juncture thereof with said lateral offset, said last-named links being of greater length than said first-named links, the pivots of said links being so positioned upon the swinging of said butts to closed relation, that a line passed through the pivots of said last-named links extends at right angles to a line passed through 50 one of said pivots and one of the pivots of the other links.

2. A hinge of the class described, comprising:

a butt having a pair of spaced apart parts; a cooperating butt having an angularly turned portion; a lateral offset on said angularly turned portion; a pair of links pivotally mounted at one of their ends between said spaced apart parts and at their opposite ends to said lateral offset; a pair of links pivotally mounted at one of their ends to said spaced apart parts and at their opposite ends to said angularly turned portion adjacent the juncture of said lateral offset therewith, said last-named links being of greater length than said first-named links and formed arcuate with the concave edge faced toward said first-named links, the location of said pivots being such that, upon a swinging of said butts to closing relative position, a line passed through the pivots of said longer links extends at right angles to a line passed through one of said last-named pivots and one of the pivots of said shorter links, the swinging of said butts to open position moving 15 said links relatively for effecting the alignment of the pivots of said shorter links with one of the pivots of said longer links immediately prior to the movement of said butts to fully open position, one of the pivots of said shorter links swinging 20 beyond said alignment upon the completion of the swinging to open position.

3. A hinge of the class described, comprising: a butt having a pair of spaced apart parts; a co-operating butt comprising a main body having an angularly turned portion; a lateral offset on said angularly turned portion extending in axial parallel relation to the longitudinal axis of said body; a pair of links pivotally mounted at one of their ends between said spaced apart parts and at their opposite ends to said lateral offset portion, said opposite ends of said links embracing said offset portion; a pair of links pivotally mounted at one of their ends to said spaced apart parts and embracing, at their opposite ends, said angularly turned portion, adjacent the juncture of said lateral offset therewith and pivoted thereto, said last-named links being of greater length than first-named links; a pin projected through 35 said first-named links for pivotally mounting the same on said spaced apart parts; a coil spring embracing said pin; a projection extending centrally outwardly from said spring and engaging in an opening formed in said first-named butt for preventing rotation of said spring on 40 said pin; and outwardly projecting angularly turned portions on the ends of said spring for engaging said second-named links and resisting swinging movement of said hinge butts upon the approach of the same to fully open position and 45 fully closed position.

JOHN LUDWIG.
